CHARLES P. KLEEBAUER, OF BROOKLYN, NEW YORK, ASSIGNOR TO COHOES ENVELOPE CO., INC., OF COHOES, NEW YORK, A CORPORATION OF NEW YORK.

SHIPPING-TAG ENVELOP.

1,382,426.

Specification of Letters Patent. Patented June 21, 1921.

Application filed August 8, 1917, Serial No. 185,052. Renewed August 31, 1920. Serial No. 407,219.

To all whom it may concern:

Be it known that I, CHARLES P. KLEEBAUER, a citizen of the United States, and a resident of the city of New York, borough of Brooklyn, in the county of Kings and State of New York, have invented a new and Improved Shipping-Tag Envelop, of which the following is a full, clear, and exact description.

10 Among the principal objects which the present invention has in view are: to provide means for reinforcing the portion of an envelop of the character mentioned to which is attached the devices whereby the envelop 15 is secured to the article shipped; to facilitate the introduction of the tying device; and to simplify the construction of the envelop.

Drawings.

20 Figure 1 is a side view of an envelop constructed and arranged in accordance with the present invention;

Fig. 2 is a detail view of the same showing the parts of the lower end of the envelop 25 spread to receive the fastening device;

Fig. 3 is a detail view of the blank of which the envelop is constructed.

Description.

30 As seen in the drawings, the completed envelop has side seams 8, which are integral with the body portion 9 and fold over to be pasted upon the back portion 10. The back portion 10 and the flap portion 11 are folded 35 on the body portion 9 at the fold lines indicated by the numerals 12 and 13 in Fig. 3.

Before folding the back portion 10 and the flap portion 11 upon the body portion 9, reinforcing patches 14 are adhered to the blank, 40 said patches extending across the lines 12 and 13. When thus adhered, the patches 14 and associated envelop structure are punched to provide the perforations 15, which are alined when said back and flap are folded on

45 the body 9. The perforations 15 are connected by an S-shaped slit 16. The ends of the slit 16 open in to the perforations 15 and in relatively opposite directions. The slit 16 forms channels through which may be forced 50 tying strings for securing the envelop in service. When the back portion 10 and flap portion 11 are folded over the body portion 9, it will be observed that the edges of the opposite ends of the envelop are severed by the

slit 16, the folded portion whereof affords 55 access to the string or tying cord.

The sections 17 and 18 of the reinforcing patches and associate structure form in conjunction with the perforations 15, hook-like structures which coöperate to hold the tying 60 cord in the perforations 15, or, in other words, to prevent the escape therefrom. It will be noticed, too, that the unbroken walls of the perforations 15 are turned toward the edge of the folded members of the envelop. 65 All strains exerted on the tying cord placed in these perforations, pull in this direction, with the result that the maximum of resistance of the reinforcing patches is obtained by the structure. 70

Claims.

1. An envelop as characterized embodying a body portion, a back portion, a flap portion, and side seams; reinforcing patches adhered to said envelop where the back and body portion, and the flap and body portion are folded; and means for attaching a tying cord to said envelop, said means embodying perforations formed in said patches, said 75 perforations being adapted to aline when the patches are folded with the body and flap portions of the envelop, and an S-shaped slit 80 connecting said perforations.

2. An envelop as characterized embodying a body portion, a back portion, a flap portion, and side seams; reinforcing patches adhered to said envelop where the back and body portion, and the flap and body portion are folded; and means for attaching a tying 85 cord to said envelop, said means embodying perforations formed in said patches, said perforations being adapted to aline when the patches are folded with the body and flap 90 portions of the envelop, and an S-shaped slit 95 connecting said perforations, said slit having entrance terminals forming passageways for admitting tying cord to said perforations.

3. An envelop as characterized embodying a body portion, a back portion, a flap portion, and side seams; reinforcing patches adhered to said envelop where the back and body portion, and the flap and body portion are folded; and means for attaching a tying 100 cord to said envelop, said means embodying 105 perforations formed in said patches, said perforations being adapted to aline when the patches are folded with the body and flap

portions of the envelop; and an S-shaped slit connecting said perforations, said slit having entrance terminals forming passageways for admitting tying cord to said perforations, said entrance terminals entering said perforations at the side thereof farthest removed from the line of the fold in the patches and associated envelop structure.

4. An envelop as characterized embodying
10 a body portion, a back portion, a flap portion, and side seams; reinforcing patches adhered to said envelop where the back and body portion, and the flap and body portion are folded; and means for attaching a tying
15 cord to said envelop, said means embodying

perforations formed in said patches, said perforations being adapted to align when the patches are folded with the body and flap portions of the envelop, and an S-shaped slit connecting said perforations, said slit having 20 entrance terminals forming passageways for admitting tying cord to said perforations, said slit corresponding in shape at opposite sides of the longitudinal median line of said patches, to locate the hook-shaped sections 25 formed by said slit at opposite sides of said median line when the envelop is folded as set forth.

CHARLES P. KLEEBAUER.
